(57) **CLAIM**

The ornamental design for a combined computer and video camera, as shown and described.

DESCRIPTION

FIG. 1 is a perspective view of a combined computer and video camera showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a bottom plan view thereof, wherein the monitor is in the open position;

FIG. 9 is a front view thereof, wherein the monitor is in the open position;

FIG. 10 is a left side view thereof, wherein the monitor is in the open position;

FIG. 11 is a bottom plan view thereof, wherein the monitor is in the open and turning position;

FIG. 12 is a perspective view thereof, wherein the monitor is in the open and turning position;

FIG. 13 is a front view thereof, wherein the monitor is in a closed inward position;

FIG. 14 is a left side view thereof, wherein the camera is in a first alternating position; and,

FIG. 15 is a left side view thereof, wherein the camera is in a second alternating position.
